UNITED STATES PATENT OFFICE.

DAVID RANKIN, OF SAN FRANCISCO, CALIFORNIA.

JACK-SCREW.

SPECIFICATION forming part of Letters Patent No. 232,846, dated October 5, 1880.

Application filed June 30, 1880. (No model.)

To all whom it may concern:

Be it known that I, DAVID RANKIN, a subject of the Queen of Great Britain, and residing at San Francisco, in the county of San 5 Francisco and State of California, have invented a new and useful Jack-Screw, of which the following is a specification.

My invention relates to improvements in jack-screws such as are used in the lifting or 10 moving of buildings and other heavy weights; and the objects of my improvements are, first, to provide a jack-screw in which the cap which supports the weight is so constructed as to give a central and not a side pressure to the 15 capstan-head and screw-threaded shaft when being worked on an incline and while the screw-shaft is being revolved or worked; second, to provide a means whereby the screw-threads of the shaft and base are relieved of 20 the superincumbent weight or pressure after the weight has been raised, and all danger of accidents which might arise from the breaking 25 of the screw-threads is avoided; third, to provide a device whereby the capstan-bar or handspike may be attached to the body of 30 the jack-screw in such manner as to form a handle by which the jack-screw may be carried from place to place; and, lastly, to provide a means whereby the capstan-bar can be operated in a small compass or space.

I attain these objects by the mechanism illustrated in the accompanying drawings, in which—

Figure 1 is a side elevation; Fig. 2, vertical 35 sectional elevation; Fig. 3, top view of cap.

Similar letters refer to similar parts throughout the several views.

The body or base A of my jack-screw I cast in the usual bell-shaped mold, and turn a 40 screw-thread for a short distance in the upper part thereof.

The stem or shaft B of the capstan-head C is provided with a screw-thread its entire length, and it engages with the screw-thread 45 of the body A.

The capstan-head C is pierced with two or a double series of capstan-holes, D D', the centers of the upper holes or openings being over the center of the web, between the lower 50 tier of holes, the object being to provide a means for working the jack in places where

it is impossible to make any but short turns of the capstan-head.

The top of the capstan-head is constructed in the form of a dome, as clearly seen in Fig. 55 2, and over this the cap or castle E fits, and is held in position by a bolt or rivet, a.

The cap or castle is hollowed out, as shown, so as to fit over the top of the capstan-head or dome, and the lower part of this cavity is 60 of greater diameter than the upper part thereof, or of that portion of the capstan-head upon which it rests and covers, the object being to permit the cap to be slightly inclined when operating or working on an incline or uneven 65 ground.

Near the upper part of the base A, I secure the knob F, which has an aperture through which the handspike G is passed, and a step is formed near the bottom of the base A, in 70 which the point of the handspike rests. A set-screw, b, serves to secure the handspike in its position, as shown.

When in operation, and the screw-shaft has been turned up a sufficient height, and it is 75 desirable that the superincumbent weight shall remain in a certain position for any length of time, I take the key or bar H, which, when not in use, hangs by a ring upon the knob F, and pass it through any two of a series of slots, 80 I I, cut in the base A, and then reverse the jack-screw a few turns, or until the lower end of the screw-shaft rests upon the said key, and the pressure will then be taken off the screw-threads and all danger of accident be avoided. 85

The part of the cap E which is applied to the weight to be operated upon is hollowed out, as shown, and the upper part or rim has a triangular groove, c, cut therein, so that it may take a firmer hold upon the weight to be 90 lifted, and at the same time not scarify it as when operating with a notched cap.

Having thus described my invention, what I claim, and desire to secure by Letters Patent, is—

1. In a jack-screw, the combination of the capstan-head constructed in the form of a dome with the cap or castle hollowed out so as to be received by the said capstan-head in such a manner as to allow of sufficient space 100 for the easy working of the parts when united, substantially as herein set forth and described.

2. In a jack-screw, the combination, with the base A and cap E, of the screw-threaded stem B and dome-shaped capstan-head C, provided with rivet-bolt *a* and a series of holes, 5 D, arranged on different planes therein for the purpose of operating the capstan-bar within a small compass or space, as specified.
3. In combination with the stem or shaft B and base or body A of a jack-screw, the key 10 or bar H, arranged substantially as shown and described, for the purpose set forth.
4. In a jack-screw, the combination of the slotted base A, perforated capstan-head C,

and cap E, all arranged and operating substantially as herein shown and set forth.

5. In a jack-screw, a carrying or lifting device consisting of a knob or projection, F, set-screw *b*, and capstan-bar G, substantially as set forth and described.

In testimony that I claim the foregoing I 20 have hereunto set my hand and seal this 2d day of June, 1880.

DAVID RANKIN. [L. S.]
